UNITED STATES PATENT OFFICE.

EDWARD H. BELDEN, OF TOLEDO, OHIO, ASSIGNOR, BY MESNE ASSIGNMENTS, TO THE WILLYS-OVERLAND COMPANY, OF TOLEDO, OHIO, A CORPORATION OF OHIO.

INTERNAL-COMBUSTION ENGINE.

Application filed August 26, 1918. Serial No. 251,510.

To all whom it may concern:

Be it known that I, EDWARD H. BELDEN, a citizen of the United States, residing at Toledo, county of Lucas, and State of Ohio, have invented certain new and useful Improvements in Internal-Combustion Engines, of which I declare the following to be a full, clear, and exact description.

This invention relates broadly to internal combustion engines and more particularly to a novel arrangement of a casting "en bloc" having a plurality of cylinders including an integral transverse inlet manifold and certain valve chambers, together with a water jacket and engine base or partial crank casing in combination with certain inlet and exhaust manifolds, carburetor and air intake therefor, arranged so that an extremely simplified construction of engine will be provided and moreover a material saving of longitudinal or lateral space occupied by the engine assembly with its co-operating elements will be obtained.

Thus the objects of this invention include the provision of a simple arrangement of multiple cylinder casing with an integral internal inlet passage therefor forming an engine unit of such character as may be readily cast, the simplified construction referred to facilitating for example the method of releasing and withdrawing the patterns from the molds for the casting, thus facilitating the casting and manufacture of the engine, the unit also providing certain inherent advantages in the construction thereof when completed.

Further objects of the invention are to provide an arrangement of separate inlet and exhaust manifolds for the engine casting to facilitate the construction of the whole assembly and to provide such inlet and exhausts that the mixture from the carburetor is heated before entering into the engine cylinders and, moreover, the air drawn in by the carburetor may also be pre-heated by the exhaust, the whole being arranged so as to provide a compact and complete assembly with the resultant saving of considerable lateral space. Moreover, by the arrangement referred to the carbureted mixture is maintained more uniformly at a constant, even temperature corresponding to and depending upon that under which the engine is working regardless of variations

in the external temperature of the air originally taken in the carburetor.

Further objects of the invention relate to the various details of constructions, arrangements of parts, and association of elements described herein, but it is to be understood that the invention in its broad concept is not limited to the details utilized in the specific embodiments illustrated as one means for carrying the invention into effect, but that the same may be varied to include any and all means capable of use as indicated herein to attain the objects hereof.

A structure illustrating one means for carrying the invention into effect and showing certain embodiments is illustrated in the drawings forming a part of this specification, in which:

Figure I is a transverse sectional view showing a four cylinder engine taken on the line I—I of Figure II;

Figure II is a part sectional and part elevational view of the engine taken on the line II—II of Figure I;

Figure III is a transverse sectional view taken on the line III—III of Figure I, certain of the parts being shown in the elevation;

Figures IV and V are sectional views taken on the line IV—IV and V—V of Figure I.

Figure VI is a transverse sectional view corresponding to Figure I, showing the invention applied to a six cylinder engine.

Figure VII is a part sectional and part elevational view of the engine illustrated in Figure VI taken on the line VII—VII of Figure VI.

Similar reference numerals refer to similar parts throughout the several views, and the sections are taken looking in the direction of the arrows at the end of the section line.

Referring to Figures I, II and III, it will be seen that by this invention there is provided a main casting 10 constituting a complete unitary casting which includes four cylinders (11, 12, 13 and 14), an integral internal and in this case transverse intake pipe 15, intake and exhaust valve chambers 17 and 18 for each cylinder, a water jacket 19 formed by the cylinder walls and outer wall 20, together with an integral engine base or an upper half of crank casing indi-

cated at 22. The internal pipe 15 referred to may of course be located longitudinally as well as transversely of the casting 10 and at any desired angle relative to a side of the 5 engine. Moreover, the crank casing 22 may have as a part thereof an integral fly wheel casing 24 located at one end thereof and a cam gear casing 25 at the opposite end thereof, as shown in Figure III, this base or half 10 crank casing 22 may also include half bearings 26 for the crank shaft of the engine, together with the bearings 27 for the engine cam shaft. The complete unitary casting referred to may also include the tappet bearing 15 hubs 28 and the valve stem bearings 29 as shown in Figures II and III.

As clearly shown in Figure I, each of the inlet valve chambers 17 for the cylinders 11 and 12 are provided with a common chamber 20 30, while the corresponding inlet valve chamber 17 for the cylinders 13 and 14 also has a common inlet chamber 31.

As a part of the lubricating system for the engine, the fly wheel casing 24 is provided 25 with an oil receiving reservoir 35 with a conduit 36 extending therefrom, as shown in Figure III to communicate with a longitudinal conduit 37 from which transverse conduits 38 branch off to supply lubricating oil 30 to the bearings 26 for the crank shaft. Each of these elements are cast integral with the casting 10. Various other details used within an internal combustion engine could also be readily cast with the casting so far described by persons skilled in the art, and it is evident that the invention is in no way limited to the use of a casting including the particular co-operating parts illustrated 35 herein, as certain of the same may be omitted 40 as an integral part of the casting and others may be added thereto. The particular casting described as heretofore intimated, is of such a character that in making the patterns for the mold from which the casting is taken 45 the same may be so constructed as to be readily withdrawn in making up the separate molds and hence the casting of the engine unit 10 is thereby facilitated.

The upper end of the casting 10 including 50 the upper ends of the cylinders, as well as the adjacent parts as illustrated in Figure I may be machined if desired so as to receive a separate cylinder head 40. The separate head 40 is adapted to cover the entire upper 55 portion of the cylinders and has cast integrally therewith a plurality of chambers 41, one for each of the cylinders 11, 12, 13 and 14 and a water return conduit 42 communicating with the water jacket 19. Referring to Figure III, it will be seen 60 that secured to the casting 10 adjacent one opening of the inlet pipe 15 is a carburetor 45, which may be of any type desired, while secured to the other end of the pipe 15 is a 65 separate two-armed inlet manifold 47, one

branch of the inlet manifold 47 leading to the chamber 30 and the other branch thereof, not shown in the drawings, communicating with the chamber 31. An exhaust manifold 50 located close to and above the inlet 70 manifold 47 has a plurality of arms 51 for communicating with the several exhaust valve chambers 18 of each of the cylinders. Any suitable means for retaining the inlet and exhaust manifolds to the casting may 75 be used and, as shown, there is provided a plurality of retainer spiders 52, having bolts 53 secured into suitable screw threaded openings 54 in the casting, as will be readily understood from reference to Figures II and 80 III.

Extending from the exhaust manifold 50 on one side of the engine into the carburetor 45 on another side thereof is an arched connecting pipe 55 having an intake terminal 56 located over the exhaust manifold 50 adapted to receive air from around the exhaust manifold 50 and deliver the same through the pipe 55 and hence by a hollow arm 58 to the carburetor 45. The pipe 55 is 90 connected with the hollow arm 58, as shown, the arm being secured to the carburetor 45 and adjacent the connections between the arm and terminal 57 of pipe 55, there is provided a plurality of openings 59 to admit 95 air directly to the arm 58, while surrounding the arm 58 is a valve in the form of a tubular sleeve 60 which may be adjusted to regulate the amount of air drawn directly into the carburetor 45 through the openings 59 rather than through the pipe 55 which receives the heated air from around the exhaust manifold 50.

By the arrangement thus described, it will be apparent that there is provided a 105 simplified, compact internal combustion engine assembly having many advantages. The casting 10 has, as a part thereof, the base and half crank casing 22, together with the cylinders thereof, the water jacket, and 110 an integral internal inlet pipe 15. Thus, as shown, the carburetor 45 may be located on one side of the engine and the intake and exhaust manifold on (in this case the opposite) another side thereof, leaving below 115 the inlet manifold 47 a space within which may be located, for example, the generator used with the engine. Moreover, the transverse inlet pipe 15 passing directly adjacent the cylinders 12 and 13, and through the 120 water jacket, as will be apparent from Figure I, provides means for materially pre-heating the inlet mixture received from the carburetor 45, thus preventing condensation of the vapor providing for a revaporization 125 of any possible vapor condensed, besides maintaining the temperature of the inlet mixture received in the cylinders at any desired uniform heat, controlled by the heat of the cylinders and water jacket. After 130

leaving the pipe 15, the mixture is maintained in heated condition by reason of the close proximity of the exhaust manifold 50 with the inlet manifold 47. It will be noted that a separate inlet manifold 47 and exhaust manifold 50, each separate from the casting 10, are provided in the construction forming a part of this invention, the same being located outside the water jacket of the engine, as it has been found that this combination of separable manifolds with the type of casting described herein is particularly capable of manufacture in an efficient manner on a large scale.

The modification shown in Figures VI and VII is substantially the same, in so far as the present invention is concerned, as that of Figures I, II and III excepting that the illustration of Figures VI and VII is of a six cylinder instead of the four cylinder type illustrated in the other figures. In this instance the transverse inlet pipe 15 is located between the two sets of three each of the cylinders of the engine as shown, while the inlet manifold 47' has several arms necessary to connect with the several inlets for the various cylinders in this embodiment of the invention, the branch 70 connecting with the inlet chamber 30', while the branch 71 connects with an inlet chamber 72 for the extra cylinder 73, the inlet chamber 30' in this case connecting with each of the cylinders 11' and 12' as shown. On the other side of the inlet pipe 15 a branch (not shown) from the inlet manifold 47' connects with the inlet chamber 74 for the other cylinder 75 and a further branch (not shown) connects with the inlet chamber 31' common to each of the cylinders 13', 14'.

It will be understood that the assembly and construction of the modification shown in Figures VI and VII is otherwise substantially the same as that of the embodiment of the invention illustrated in Figures I to V and a further description thereof is, therefore, deemed unnecessary.

As heretofore indicated, it is to be understood that this invention is capable of considerable variation from the details of the construction described herein without departing from the spirit and scope of the invention as pointed out in the appended claims.

Having thus described my invention, what I claim as new and desire to secure by Letters Patent, is:

1. The method of supplying a mixture to an internal combustion engine which consists in heating the air supply from the ex-

haust gases, conveying the heated air over the engine cylinders to a carburetor, charging the heated air through a carburetor to form a fuel mixture, passing the mixture through a heated conduit between two of the cylinders of the engine, and finally admitting the mixture to the engine.

2. In an internal combustion engine the combination of a plurality of cylinders, intake and exhaust manifolds at one side of said engine, a mixture conduit connected at one end with said intake manifold and extending transversely between two of said cylinders, a carburetor located on the opposite side of said engine and connected with the other end of said conduit, and an air supply tube extending from a point adjacent said exhaust manifold over said cylinders to said carburetor.

3. In an internal combustion engine, the combination of a plurality of aligned cylinders, intake and exhaust manifolds at one side of said engine, a mixture conduit integral with said cylinders and extending transversely between two thereof, one end of said conduit being connected with said inlet manifold, a carburetor connected to the opposite end of said conduit, a stove on said exhaust manifold and an arched conduit connecting said stove and said carburetor and extending up over the top of said cylinders.

4. The method of supplying a mixture to internal combustion engines which consists in heating the main air supply passing it thru a conduit to a carburetor, slightly heating the conduit, adding cool air to said heated air, charging this air thru the carburetor to form a fuel, passing it thru a conduit, heating said conduit to a greater degree than the first mentioned conduit and admitting this heated mixture to the engine.

5. In an internal combustion engine construction, the combination of a plurality of cylinders, inlet and exhaust manifolds located on one side of said cylinders, a carburetor located on the opposite side of said cylinders, means passing over said cylinders to supply heated air from around said exhaust manifold to said carburetor, means adjacent the carburetor for supplying cold air to said heated air, and means to supply the carbureted mixture to said inlet manifold, said means being heated by the cylinders to prevent condensation of said mixture before entering the said cylinders.

In testimony whereof, I affix my signature.

EDWARD H. BELDEN.
